UNITED STATES PATENT OFFICE.

CHARLES MEE, OF CORTLAND, NEW YORK.

LOUNGE.

SPECIFICATION forming part of Letters Patent No. 446,874, dated February 24, 1891.

Application filed February 1, 1889. Serial No. 298,403. (No model.)

To all whom it may concern:

Be it known that I, CHARLES MEE, a citizen of the United States, residing at Cortland, in the county of Cortland and State of New York, 5 have invented an Improvement in Lounges, of which the following is a specification.

My invention relates to improvements in lounges; and the objects of my invention are to render the said lounge adjustable at the 10 will and pleasure of the user, and to enable the said user to change the same into a right-hand lounge, a left-hand lounge, or a settee or tête-à-tête, as he may desire and his convenience may require, or, if he desires, to turn the 15 same into a flat surface for a bed, or any other use to which the same may be applied. I attain these objects by the mechanism or contrivances illustrated in the accompanying drawings, in which—

20 Figure 1 is a front view of my invention, and also showing the sectional end view of the same. Fig. 2 is a back view of my invention. Fig. 3 is a sectional front view of my invention with the head-rests thereof attached thereto, one being elevated and the other lying horizontal.

Similar letters refer to similar parts throughout the several views.

25 A is the frame of the bed of the lounge. B B are recesses in each end of the front and back rails of the said frame, making a firm and substantial rest for the head-rest of said lounge when lying in a horizontal position.

30 C C are braces, one thereof being attached by means of a hinge to the cross-bar at each end of the frame of the bed of said lounge at D, there being a slot in the upper end of said braces C C at E, said slot being of sufficient 35 length for the purposes of my invention. Said braces may be made out of wood, iron, or any other suitable material. On each side of said slot E and on the inner side of said braces C C, I place and attach a corrugated-iron facing. This facing, however, may be 40 made of any other metal. This facing in the drawings is marked E'.

45 F F are head-rests, one being attached to each end of the frame of the bed of said lounge at and by means of the hinges G G G G. These head-rests are so constructed that when

lying in a horizontal position they shall fit into the recesses B B and rest upon the projection thereof, thus securing for them, when in that position, a firm and substantial rest. 55 This may be accomplished in part by aid of the blocks H H H H, placed at and firmly attached to each corner of the frame A, and by similar blocks H' H' H' H', placed at the lower end and inside the head-rests F F and 60 firmly attached thereto, said blocks on the frame and head-rests being placed immediately under the hinges G G G G; or this may be accomplished by any other device which shall raise the said hinges G G G G up even 65 with the top of the upholstering-strip. The said head-rests F F shall also be so constructed that the outer facing f' thereof shall lap over and work entirely free and independent of the front of the frame A, thus affording a 70 complete cover to the joints and recesses in the front rail thereof. On the outer and under side of each of said head-rests F F, I place a metal corrugated washer I I with a hole in the center thereof, said washer being so 75 placed as to come in contact with the surface of the corrugated plates or facings E'.

Passing through the slot E and the hole in the washers I I is a set-screw or clamp-screw J, whereby said facings and washers are 80 brought in contact with each other.

K is the back of said lounge.

M M are bars attached to the back K by the pivots n n. o o are notches in the ends of said bars in the alternate sides thereof to receive the pins p p p p, protruding from the outside of said back and frame A, and by means of said bars, notches, and pins said back K is held in position when it is desired to use my invention as a lounge or tête-à-tête. 90 Said back K is fastened to the said frame A by means of the hinges L L.

R is a brace fastened to the back K by the hinge S, the lower end hanging loose. The lower end of the said brace R may be supplied with a caster or not, as desired. The object of the brace R is to furnish a support to the back K when it is let down to form a bed. Now it will be seen that by loosening the set-screw J in either of said head-rests 95 100 that particular head-rest may be elevated to any incline desired or placed in a horizontal

position, and, if elevated, retained in its position by resetting said screw, and by thus doing said lounge may be converted into a right-hand or left-hand lounge, or by raising both 5 head-rests it may be converted into a tête-à-tête, as desired, and it will also be seen that by lowering either or both of said head-rests and by detaching the bars M M from the pins p p and bringing the same to a position parallel with the frame A and extending the brace R for a support the back K may be laid down and my invention be thus converted 10 into a bed.

Having thus described my said invention, 15 what I claim as my invention, and desire to secure by Letters Patent, is—

A lounge having a frame proper with end and side rails, the side rails recessed at their ends and having a head-rest resting in the recess and connected by hinges to the frame proper, said rest having an outer facing which laps past the joint at the front of the frame, and a brace hinged to the frame and having a roughened facing which engages a roughened washer on the head-rest and is adjustable to hold the head-rest at different angles by a clamp-screw, all substantially as described.

CHAS. MEE.
